Maschinenfabrik Augsburg-Nürnberg A. G., Augsburg,
Germany, a corporation of Germany

Application July 17, 1951, Serial No. 237,229

Claims priority, application Germany January 20, 1951

4 Claims. (Cl. 253—39.15)

This invention relates to certain improvements in regard to the thermal protection of steel rotors in gas turbines with high temperatures of the propellant gas.

It is an object of the present invention to provide means for protecting the blade-carrying elements, i. e. the steel discs or drums of an axial-flow one- or multi-stage turbine rotor against the very high temperatures of the propellant which necessitate the provision of moving blades of special ceramic materials or other materials adapted for such high temperatures. The provision of ceramic blades is urged by the well-known inferiority of metallic materials as regards creep strength, and also by the tendency of reducing to a minimum the loss of heat energy (e. g. by conduction into the metal rotor) which is suitable for the production of mechanical energy.

In view of the exacting conditions of operation existing in the hot rim of the turbine rotor rotating at a high speed it is very difficult to provide effective and reliable heat barrier zones on the surface thereof.

According to the present invention this task is solved in such a way that more particularly the superficies or surface portions of the rotor in front of and behind the blade-grids or stages are interrupted, by cutting grooves of a suitable cross section and depth, into comb-like strips, extending in an axial and/or in a peripheral direction, depending on the local conditions such as direction of gas flow. These strips are shaped so that they are still in a reliable mechanical coherence with the rotor bodies. The upper ends of the walls between the grooves are then turned over, as by rolling, whereby cavities with practically stationary gas layers are obtained. These gas layers together with the reduced cross sections for thermal conduction to the solid disc body result in an effective reduction of the rim temperatures, from the value determined by the driving gas, to sufficiently lower values in the portion carrying the blades, such lower values being required to ensure a satisfactory creep strength of the steel. Thus the thermal tensions in the blade-carrying part of the rotor, especially when starting and on rapid changes of the load, also become smaller. It is also possible, by the construction according to the present invention, to increase the wall thickness of the drum and thus to increase the load-carrying capacity of the rotor. By grinding the outer diameter of the rolled-down intermediate walls it is easily possible to compensate for small plays of the guide blades with respect to the rotor thus protected. It is also possible, by known means, to feed an air current through the cavities obtained by rolling over the intermediate walls, whereby the insulation is increased in known manner. By the formation of air screens issuing from the cavities in a radial outward direction through gaps in the rolled over walls, the transfer of heat from the passing hot propellant gases to the rotor can be substantially reduced.

According to a further modification of the invention a particularly effective heat insulation can also be achieved in such a way that the cross sections available for the

2

transmission of heat from the heated outer surfaces of the rotor to the supporting solid core thereof are reduced, by transverse and crosswise grooves, to cross sections in the form of thin studs. The possibility of a flow of gas between the studs, which flow would impair the intended insulating effect, is practically eliminated by coating the studs with a ceramic or enamel layer by which the free space between the studs is greatly narrowed down. Owing to the spiral movement of the heating gas envelope around the rotor and by a corresponding direction of the grooves the formation of a convection current of the propellant gas within the narrow gaps left is avoided and thus a substantial reduction of the insulating effect of the layer is avoided. Owing to the fact that the studs are substantially unaffected by the mechanical strains within the carrier disc or drum a reliable durability of the heat insulating layer can be ensured if the expansion characteristics of the coating layer are approximately adapted to the data of the steel material.

According to a further feature of the invention it is also contemplated to fill up the entire interspace between the studs with a self-hardening heat-resistant cement of poor thermal conductivity and suitable characteristics of heat elongation, whereby the heat-insulating layer at the surface of the rotor will be nearly perfect.

Other and further objects, features and advantages of the invention will be pointed out hereinafter and appear in the appended claims forming part of the application.

In the accompanying drawings several now preferred embodiments of the invention are shown by way of illustration and not by way of limitation.

Fig. 1 is a fragmentary axial section through a turbine rotor,

Fig. 2 is an axial section through the heat-insulating layer 3 of a rotor, with the intermediate walls partly bent over,

Fig. 3 is an axial section through a modified form of heat insulating layer, with the intermediate walls partly bent over,

Fig. 4 is a plan view of a part of the rotor rim with longitudinal and transverse grooves,

Fig. 5 is an axial or transverse section through one row of studs 13 of Fig. 4 showing a heat insulating layer having longitudinal and transverse grooves, and

Fig. 6 is a fragmentary plan view of the surface of the rotor of Fig. 1.

Referring now to the drawings in greater detail, it will be seen that according to Fig. 1 the blades 2 are arranged in peripheral grooves 1 of the turbine rotor 15 with the root portions 16 of the blades retained in the grooves 1 in known manner including, for example, the spacing inserts 17. The heat insulating layers at the superficies of the disc or drum before and behind the blade grids or stages are denoted 3, and are illustrated as the form shown in Fig. 2. For some high temperature operating conditions requiring additional heat insulation of the rotor, an axial boring 18 is provided in the rotor from which radial passages 19 branch off and open into an axial groove 20 at the rotor surface covered by cover plate 21. The circumferential grooves or spaces 6 open into the axial groove 20 so that a coolant may be circulated through the groove 6 by being introduced into axial boring 18 and, thence, through radial channels 19 to groove 20. According to Fig. 2 these insulating layers are formed by annular grooves 4 worked into the surface, the outer portions of the intermediate walls 5 between these grooves being bent over to form hollow spaces 6 containing either a stagnant gas layer or being traversed by cooling air.

In the embodiment shown in Fig. 3 the intermediate walls 7 are provided with two brims or tabs 8 and 9 which are bent over to opposite sides and together with

the tabs 8 and 9 of the adjacent walls form the upper closure of the hollow-spaces 10. Depending on the direction of the gas flow through the turbine, the grooves and the hollow spaces 6, or 10, extend transversely to the longitudinal axis of the rotor or parallel thereto and across the direction of gas flow.

In the modification of the heat-insulating layer as per Figs. 4 and 5 transverse and longitudinal grooves 11 and 12 are provided, subdividing the insulating layer into single studs 13 which are provided with a heat-resistant coating 14 of ceramic material, enamel or the like, whereby the grooves 11 and 12 are narrowed down to small gaps, Fig. 5. If desired it is also possible to fill up the grooves 11 and 12 entirely with a heat-resistant insulating layer.

The production of the heat-insulating layer according to the invention is very simple and offers the advantage that loose screening elements are avoided whose reliable fastening on the rotor is oftentimes very difficult owing to the high speeds.

While the invention has been described in detail with respect to certain now preferred examples and embodiments of the invention it will be understood by those skilled in the art after understanding the invention that various changes and modifications may be made without departing from the spirit and scope of the invention and it is intended, therefore, to cover all such changes and modifications in the appended claims.

What is claimed is:

1. In a high temperature gas turbine having a metal rotor with a plurality of stages of turbine blades thereon and in which the surface of said rotor between said adjacent stages is directly exposed to high temperature gas flow through said turbine, a heat insulating layer for said exposed surface of said rotor between said adjacent stages comprising a plurality of thin projections at said exposed rotor surface defining therebetween a plurality of circumferential annular grooves forming dead gas spaces, said projections being relatively thin for reducing heat conduction from said high temperature gas flow to said rotor and the cross-section of said spaces between said projections being relatively small avoiding convection currents in said spaces, and means for at least partially closing said spaces at the radially outer portion thereof for reducing aerodynamic flow resistance of said exposed rotor surface.

2. In a high temperature gas turbine having a metal rotor with a plurality of stages of turbine blades thereon and in which the surface of said rotor between said adjacent stages is directly exposed to high temperature gas flow through said turbine, a heat insulating layer for said exposed surface of said rotor between said adjacent stages comprising a plurality of thin projections on said exposed rotor surface defining therebetween a plurality of circumferential annular grooves forming insulating gas spaces for reducing heat conduction from said high temperature gas flow to said rotor, the radially outer portions of said spaces forming at least a partial closure for said spaces to reduce aerodynamic flow resistance thereof,

and the radially inner portions of said spaces defining a heat insulating layer interposed between said high temperature gas flow and said rotor.

3. In a high temperature gas turbine having a metal rotor with a plurality of stages of turbine blades thereon and in which the surface of said rotor between said adjacent stages is directly exposed to high temperature gas flow through said turbine, a heat insulating layer for said exposed surface of said rotor between said adjacent stages comprising a plurality of thin projections on said exposed rotor surface defining therebetween a plurality of circumferential annular grooves forming insulating gas spaces for reducing heat conduction from said high temperature gas flow to said rotor, the radially outer portions of said projections forming at least a partial closure at said spaces to reduce aerodynamic flow resistance thereof, the radially inner portions of said spaces defining a heat insulating layer interposed between said high temperature gas flow and said rotor, and means for supplying a heat insulating coolant into said spaces.

4. In a high temperature gas turbine having a metal rotor with a plurality of stages of turbine blades thereon and in which the surface of said rotor between said adjacent stages is directly exposed to high temperature gas flow through said turbine, a heat insulating layer for said exposed surface of said rotor between said adjacent stages comprising a plurality of thin projections on said exposed rotor surface defining therebetween a plurality of circumferential annular grooves forming insulating gas spaces for reducing heat conduction from said high temperature gas flow to said rotor, the radially outer portions of said projections forming at least a partial closure for said spaces to reduce aerodynamic flow resistance thereof, the radially inner portions of said spaces defining a heat insulating layer interposed between said high temperature gas flow and said rotor, and passage means through said partial closure communicating between said spaces and the outer surface of said closure for passage of low temperature gas from said spaces to form a heat insulating layer over the outer surface of said rotor.
